SWITCH-ACTUATING MECHANISM FOR
SEAMING MACHINES

Hans Hacklander, Linden, N. J., assignor to The
Singer Manufacturing Company, Elizabeth,
N. J., a corporation of New Jersey

Application July 20, 1950, Serial No. 174,881

8 Claims. (Cl. 219—47)

1

This invention relates to a switch for controlling the turning on and off of an electron tube oscillator responsive to the starting and stopping of the feed of the material being advanced through a radio-frequency field supplied by said oscillator.

More particularly, this invention relates to a switch-actuating mechanism which is responsive to changes in the tension of a belt which transmits driving torque to the feeding mechanism of a seaming machine.

Heretofore, this turning on and off of the oscillator has been accomplished by a switch mounted for actuation by the foot-treadle which is operated to clutch and declutch the machine shaft and the driving motor in the customary manner of electric power transmitters. This has not proven to be entirely satisfactory due to the necessity of frequent readjustments of the switch to compensate for the wear of the clutch and the brake surfaces. That is to say, the proper timing of the switch actuation relative to the feed actuation is made difficult by the fact that the switch actuator is too remote from the feeding mechanism.

It is a primary object of this invention to provide a switch-actuating mechanism which is operative responsive to changes in the tension of a belt which transmits driving torque to the feeding mechanism of a seaming machine.

The invention will be better understood from the following description when considered in connection with the accompanying drawings, and its scope will be pointed out in the appended claims.

In the drawings:

Fig. 1 is a front elevation of an electronic seaming machine showing the application thereto of a switch-actuating mechanism embodying the invention.

Fig. 2 is an end elevation of the switch-actuating mechanism shown in Fig. 1.

Fig. 3 is a front elevation of the switch-actuating mechanism shown in Fig. 2.

Fig. 4 is a section taken on line 4—4 of Fig. 2.

Fig. 5 is a section taken on line 5—5 of Fig. 2.

Referring to Fig. 1, 10 denotes a table top to which is secured a bonding machine 11 of the type shown and described in the Hacklander Patent No. 2,432,412 and to which reference may be had for a more complete understanding of its structure.

Carried on the under side of the table top 10 is an electric transmitter 12 which has its power take-off pulley 13 connected by a belt 14 to the pulley of a balance wheel 15 of the bonding ma-

2

chine 11. The electric transmitter 12 may be of the type shown and described in the Peets et al. Patent No. 2,004,055, to which reference may be had for a more complete understanding of the operation thereof. The transmitter is brought into effective operation by actuation of a pivotally supported treadle 16, acting through a rod 17 connecting the treadle 16 and the operating lever 18 of the transmitter 12. To start the machine, the operator pushes down on the toe-portion of the treadle 16. This causes the transmitter clutch to engage and, through the pulley 13, belt 14 and balance wheel 15, to rotate the main shaft of the bonding machine 11 in a manner well-known in the art.

Feeding mechanism and electrode reciprocating mechanism are, as is customary, operatively connected to the main shaft so that feeding begins as soon as the balance wheel 15 starts to turn. An electron tube oscillator 19 generates radio-frequency energy which is conducted to electrodes 20 and 21 by conducting wires indicated diagrammatically by lines 22 and 23 respectively in Fig. 1. Also connected to the oscillator 19 are control wires 24 and 25 which terminate externally at the terminals 26 and 27 of a switch 28. Closure of said switch 28 operates to turn on the oscillator 19 in any known manner, such, for example, as is shown in the Fuge Patent No. 2,487,432, wherein the oscillator output is controlled by turning on and off the D. C. plate voltage supplied to the oscillator tubes by operation of a relay. That is to say, the switch 28 may be connected to control the energizing of a plate relay for the oscillator 19.

The foregoing arrangement is well-known conventional practice for bonding machines employing oscillators for furnishing the radio-frequency energy. There will now be described a novel mechanism for actuating the switch 28 so that the oscillator is turned on and off in precise timed relation to the starting and stopping of the feeding mechanism and independently of any changing condition of transmitter operation such as that due to normal wear of the clutch and brake surfaces.

Referring now to Figures 2 and 3, an upstanding sheetmetal supporting frame 29 is secured to the table top 10 by means of wood screws 30—30. The frame is formed with a turned-over edge portion or flange 31 which is so shaped as to form with the upright portion a cover or guard for the belt loop including the pulley portion of the hand wheel 15, but leaving the hand wheel itself exposed for the usual manipulation thereof.

A lever 32 is formed intermediate its ends with a pivot stud 33 which is journaled in a bushing 34 secured to said supporting frame 29. The stud 33 is retained in said bushing 34 by means of a collar 35 secured to said stud by means of a set-screw 36.

The lever 32 is formed at one end with a hollow stud 37 which carries a free-running pulley 38 retained thereon by means of a washer 39 and a cap-screw 40 threaded into said stud. A diametral bore 41 communicates with the axial bore 42 of the stud 37 to provide a path for lubricating oil applied to the aperture 43 of the oiler 44, to conduct said oil to the bearing surfaces of the stud 37 and the pulley 38. The oiler 44 projects through a slotted aperture 45 in the frame 29 to be accessible from the exterior of the frame. The opposite end of the lever projects through a slotted aperture 46 in the forward vertical edge portion 31 of the frame 29 and terminates in a handle 46 to provide convenient means for manual operation of the lever. Overlying the top and bottom edges of the aperture are stop pieces 47—48 adjustably secured in place by means of clamps 49—49 fastened to said frame by nuts 49—49 and bolts 50—50. These stop-pieces 47 may be positioned to fix the limits for the movement of said lever 32.

A tension spring 51, secured to the lever 32 at a point adjacent the hand-end thereof, is anchored to a lug 52 adjustably secured to the frame by means of a tap screw 53, and normally biases the lever to the position shown in Fig. 2, against the lower stop-piece 47. It will be seen that, in this position, the pulley 38 engages the inner side of the pulling run 54 of the belt 14 and puts a slight hump in this run of the belt, which corresponds to the condition of the machine at rest with no driving force applied to the belt.

In this condition, the lever 32 acting through a roller 55 and a leaf spring 56 actuator of the switch 28 holds said switch in its open contact position. This corresponds to the "off" condition of the oscillator and no radio-frequency energy is delivered to the electrodes 20 and 21. The switch 28 is adjustably mounted on the frame as shown, by means of screws 57—57 which pass through apertures in the body portion of the switch 28 and are tapped into a clamping plate 58, as seen best in Fig. 5. An elongated slot 59 in the frame permits the switch to be adjusted by pivoting it about one of the mounting screws to secure proper positioning for satisfactory actuation by movement of the lever 32. It will be understood that the switch 28 per se is a single-pole, single throw switch of the well-known, normally-closed, pressure-sensitive type, which requires very small movement of the actuator to change from a fully open to a fully closed condition or vice versa.

When the operator pushes down on the toe-portion of the treadle 16 to start the machine 11, the transmitter clutch is engaged, and driving force is applied to the pulley 13 which sets up a driving tension in the pulley run 54 of the belt in the direction indicated by the arrow in Fig. 2. The tendency of this tension is to reduce the hump at the pulley 38 and to straighten out the belt run; and in so doing, the lever 32 is turned clockwise on its pivot as viewed in Fig. 1 and against the bias force exerted by the spring 51. This allows the leaf spring actuator 56 to move upwardly and close the switch contacts, thus turning on the oscillator 19 to furnish radio-fre-

quency energy to the electrodes 20 and 21 by way of lines 22 and 23.

When the treadle 16 is heeled to stop the machine, the transmitter clutch is disengaged and the driving tension in the pulling run 54 of the belt decreases rapidly permitting the spring 51 to return the lever 32 to its normal position, thus actuating the switch 28 to open its contacts and turn off the oscillator 19.

It is clear from this description that the switch 28 is actuated responsively to the establishing and releasing of driving tension in the pulling run 54 of the belt 14 which, in turn, is directly coincidental with the starting and stopping of the feeding mechanism of the bonding machine 11. Further, since the switch actuation is a function of a condition on the power take-off side of the power transmitter 12, it is independent of any time lags between treadle operation and the actual clutching or braking of the power transmitter and so is not subject to the adverse effects on the switch operation timing of the wear of the brake and clutch surfaces.

The handle 46 on the lever 32 provides a readily accessible means for manually actuating the switch 28 to turn on the oscillator 19 without starting the machine 11, as is desirable and necessary when tacking, for example.

A very practical feature of this structure is the ease with which it may be attached to existing machines in the field, requiring but two mechanical fastenings (screws 30—30) and two electrical connections (to terminals 26 and 27) for the complete installation.

A slotted aperture 60 (Fig. 4), provided in the edge 31 of the frame 29, permits the entire assembly to be readily swung away from the end of the machine 11 after loosening but not removing the screws 30—30. This is of importance, in gaining ready access to the belt and to the interior parts of the mechanism.

Although this invention has been illustrated in connection with the turning on and off of an oscillator responsively to the starting and stopping of the feed of a bonding machine, it is to be understood that it is not so limited, but includes within its scope, application to any seaming machine wherein starting and stopping is occasioned by change in the tension of the driving belt, and where it is desired to operate some auxiliary device, such as a trimmer, at the beginning and/or at the end of a seaming cycle.

Having thus set forth the nature of the invention, what I claim herein is:

1. In combination, a seaming machine having a feeding mechanism, a driven member for actuating said feeding mechanism, an endless driving member in driving engagement with said driven member, means for starting and stopping said driving member, an electric circuit, a switch connected to said circuit, and an operator for actuating said switch responsively to changes in the driving tension in said driving member incident to starting and stopping said driving member, whereby said circuit is switched responsively to the starting and stopping of said feeding mechanism.

2. In combination, a seaming machine having electrodes and a feeding mechanism, a driven member for actuating said feeding mechanism, an endless driving member in driving engagement with said driven member, means for starting and stopping said driving member, a radio-frequency oscillator electrically connected to said electrodes, a switch for turning on and off said

oscillator, and mechanism responsive to variations in the driving tension in said endless driving member incident to starting and stopping said driving member for actuating said switch.

3. In combination, a bonding machine, a driving belt for said machine, a radio-frequency oscillator electrically connected to said machine, a switch for turning on and off said oscillator, a pivoted lever for operating said switch, a free-running pulley secured to one end of said lever and resiliently biased to engage the driving side of said belt so that increased tension in said belt, occasioned by starting said machine, operates to turn said lever about its pivot to close said switch and turn on said oscillator.

4. In combination, a seaming machine having a driving belt and belt pulley, a table for supporting said machine, and a belt-tension-responsive switch-operating means comprising a supporting frame removably secured to the top of said table and shaped to provide a guard for the belt and belt pulley, a switch adjustably mounted on said frame, a lever for actuating said switch and pivoted intermediate its ends on said frame, a free-running pulley secured to one arm of said lever, a biasing member secured to the other arm of said lever to urge said pulley in a direction to engage said belt on its pulling side, whereby changes in the driving tension in said belt, occasioned by starting and stopping said machine, are translated into motion of said lever about its pivot with attendant actuation of said switch.

5. In combination, a seaming machine, a driving belt for said machine, an electrically-controlled auxiliary device, a switch for controlling said device, a pivoted lever for operating said switch, a free-running pulley secured to one arm of said lever and resiliently biased to engage the pulling side of said belt thereby to distort the normally straight run of said belt, and means for selectively establishing driving tension in said belt to start said machine, whereby said tension, acting to decrease said distortion, imparts to said lever a turning moment sufficient to overcome said bias, rotates the lever and operates said switch.

6. In a seaming machine, feeding mechanism, a shaft for driving said feeding mechanism, a belt pulley secured to said shaft, a belt for driving said pulley, means for selectively establishing driving tension in said belt to actuate said feeding mechanism, a supporting frame shaped to provide a guard for the belt and belt pulley, a switch adjustably mounted on said frame, a lever for actuating said switch and pivoted intermediate

its ends on said frame, a free-running pulley secured to one arm of said lever, and a biasing member secured to the other arm of said lever to urge the free-running pulley into engagement with the pulling side of said belt, whereby changes in the tension of said belt occasioned by starting and stopping said feeding mechanism are translated into motion of said arm about its pivot with attendant actuation of said switch.

10 7. In combination, a belt-driven seaming machine, a belt-tension-responsive switch mechanism comprising a pressure-sensitive switch, a centrally pivoted arm in operative relation with said switch, a free-running pulley secured to one end of said arm, said arm being biased to urge said pulley into limited engagement with the driving belt of said machine on the pulling side thereof whereby to distort the run of said belt out of its normally straight path so that increased tension in said belt occasioned by starting said machine tends to straighten said run of said belt and imparts to said arm through said pulley a turning moment sufficient to overcome the biasing force and turn the arm to actuate the switch.

25 8. A unitary switch assembly and belt guard for a belt-driven seaming machine, comprising an upstanding supporting frame adapted to be removably secured to a table-top adjacent the pulley-end of said machine to cover the belt and pulley thereof, a pressure-sensitive switch mounted on the interior of said frame, a lever arm pivoted on said frame in operative relation to said switch, a pulley carried by said arm and biased for engagement with the driving side of said belt, and a portion of said lever arm extending through an apertured portion of said frame to provide external means for manually operating said switch.

HANS HACKLANDER.
